UNITED STATES PATENT OFFICE.

MANTON W. TREADGOLD, OF BANDON, OREGON.

SHOE-LACE FASTENER.

1,279,043.

Specification of Letters Patent. Patented Sept. 17, 1918.

Application filed November 7, 1917. Serial No. 200,779.

To all whom it may concern:

Be it known that I, MANTON W. TREADGOLD, a citizen of the United States, residing at Bandon, in the county of Coos and State 5 of Oregon, have invented new and useful Improvements in Shoe-Lace Fasteners, of which the following is a specification.

This invention relates to cord and rope holding clasps, and more especially those 10 having a pivoted part and a cam lever; and the object of the same is to produce an improved clasp for fastening shoe laces and the like.

Heretofore a clasp of this kind has comprised a base and a substantially L-shaped part pivoted at its angle thereto, one arm being a handle by which the part was moved on its pivot and the other arm projecting toward the base and clamping the cord against 15 it. My invention involves this principle in so far as it includes a base and a pivot part, but the working or biting arm of the pivoted part does not project from the point 20 where it is pivoted. On the contrary it projects from what might be called the other 25 end of the handle so that there is considerable resiliency between the pivot and the tip of the biting part.

Details will be found in the following 30 specification, and reference is made to the accompanying drawings wherein—

Figure 1 is a perspective view of this device applied to a piece of leather, showing a shoe string or lace as clasped therein.

Fig. 2 is an enlarged longitudinal sectional view, showing the string as clasped in full lines and the parts turned in dotted lines to release the string.

In the drawings I have shown in Fig. 1 40 a piece of material such as leather L to which this clasp is attached, and a lace or shoestring S to be held therein, but I do not wish to be limited to this use of the device. The clasp comprises a base 1 secured to the 45 material by rivets or other clasping means, ears 2 upstanding from the sides of the base, and a pivot pin 3 connecting their upper ends. On this pivot pin is mounted an eye 4 at the extremity of one arm of the substantially U-shaped pivoted part. From the eye 50 this arm extends outward as at 5 and then bends as at 6 and returns inward as at 7,

and the tip 8 of this arm is then turned away from the eye. The parts are entirely of metal, and the proportions are immaterial.

In the use of this device the cord or string S is passed over the base between the upstanding ears and under the pivot pin, the pivoted part being turned back as seen in dotted lines in Fig. 2. When the cord or 60 string has been adjusted to the desired point, the pivoted part is turned down into the position shown in full lines in Fig. 2. At this time its tip bites on the string and 65 presses the latter against the base plate, and the resilience of the U-shaped member is exerted to hold the tip in biting engagement. Obviously said tip stands between the pivot pin and the base plate, so that strain on the 70 string S only draws it tighter. When it is desired to release the clasp, the finger or thumb nail is inserted under the bend and the pivoted part raised to the position shown in dotted lines in Fig. 2, and the tip 75 at this time comes out of contact with the string so that the latter is free.

Another feature of my invention is the protection afforded to the pivoted part by the peculiar shape of the ears 2. It will be 80 observed that while these are or may be beveled off at their rear sides or edges, their front edges or ends are carried alongside the pivoted part into corners which are preferably practically right angular as 85 shown at 9, their upper edges standing well above the position of the pivoted part when it is clasping the string as shown at 10, and their front ends 11 being at least coincident with the bend 6. The result is that these 90 ears by their shape prevent the catching of extraneous objects on the pivoted part and either throwing the latter upward to a position where the spring is released as shown in Fig. 2, or tearing the said object; and 95 yet when the clasp is to be opened the tip of the finger can be inserted over the string and under the bend 6, and the latter raised very easily.

What is claimed as new is—

A cord clamp comprising a base plate, upstanding parallel spaced ears thereon, a pivot pin connecting the rear portions of said ears, and a substantially U-shaped

clamping member of a length to be housed between said ears with its bight co-incident with their front ends, the upper arm of said member being bent outwardly at its end 5 into an eye revolubly surrounding said pivot pin and the lower arm of said member hav-

ing a deflected tip yieldingly projecting toward the base plate to clamp a cord upon said base plate, the bight of said clamping member serving as a handle.

10

In testimony whereof I affix my signature.

MANTON W. TREADGOLD.
